(57) **CLAIM**

(56) **References Cited**

The ornamental design for a stand for television receiver, as shown and described.

U.S. PATENT DOCUMENTS

DESCRIPTION

D183,617 S	9/1958	Klein
D234,068 S	1/1975	Mudde
D239,487 S	4/1976	Hysten
D240,185 S	6/1976	Rosen
D268,555 S	4/1983	Rosen
D289,839 S	* 5/1987	Kouzoujian D6/489
D328,989 S	* 9/1992	Leonard D6/477
D371,472 S	* 7/1996	Herbst D6/480

FIG. 1 is a perspective view of a stand for television receiver showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
